SYSTEM OF CONTROL.

1,298,943.

Specification of Letters Patent.

Patented Apr. 1, 1919.

Application filed May 4, 1915. Serial No. 25,714.

To all whom it may concern:

Be it known that we, RUDOLF E. HELLMUND, a subject of the German Empire, and a resident of Pittsburgh, in the county of Allegheny and State of Pennsylvania, and RALPH E. FERRIS, a citizen of the United States, and a resident of Swissvale, in the county of Allegheny and State of Pennsylvania, have invented a new and useful Improvement in Systems of Control, of which the following is a specification.

Our invention relates to systems of control, and it has special reference to the regenerative control of direct-current motors for electric railway vehicles and the like.

One of the objects of our invention is to provide a system of the above-indicated character which shall be effective and reliable in operation and which shall embody certain automatic or inherent regulating characteristics to prevent undesirable current surges and to maintain a substantially constant regenerated current.

Another object of our invention is to provide a system of the class in question which may readily be adapted for use during the accelerating periods of the motors to reduce the current peaks and to produce a relatively smooth acceleration of the vehicle.

In the co-pending application of R. E. Hellmund, Serial No. 860,612, filed September 8, 1914, and assigned to the Westinghouse Electric & Manufacturing Company, is shown and described a system for obtaining a negative compound effect during regenerative operation, such effect being secured by connecting a portion of the field-winding turns to be negatively or oppositely energized with respect to the remaining field-winding turns and the armature, thereby inherently causing a relatively rapid weakening of the effective field flux upon an increase of the regenerated current. However, in motors of the field-control type, the system in question sometimes requires still further subdivision of the field winding to provide proper regenerative conditions, thus leading to undesirable and expensive complications in the motor connections. Moreover, in case an exciting machine is employed for the main motor-field excitation during the regenerative period, if a battery is used to energize the exciter field winding, it becomes impossible to make use of

such negative or oppositely-energized field-winding turns in the exciter. Where a dynamotor is used as an exciter, if such negative turns are utilized in its field winding they act only temporarily, upon a change in the regenerated current, until the dynamotor has readjusted its speed to the new conditions.

According to our present invention, therefore, we provide a system for accomplishing the above-stated objects while obviating the disadvantages mentioned, as hereinafter more fully set forth.

In the accompanying drawing, Figure 1 is a simplified diagrammatic view of the main circuits of a system of regenerative control embodying our invention; and Figs. 2, 3 and 4 are similar views of modification of the system that is shown in Fig. 1.

Referring to Fig. 1 of the drawing, the system here shown comprises a plurality of suitable supply-circuit conductors respectively marked "Trolley" and "Ground"; a dynamo-electric machine, such as an electric-vehicle motor, having an armature A and a series-connected field-magnet winding F; a motor-generator apparatus, preferably of the familiar dynamotor type, having a motor-armature winding M and a series-connected generator-armature winding G, the dynamotor being provided with a common exciting field-magnet winding E that is connected across the two armature windings M and G; a translating device, such as a resistor R, that is connected from a point intermediate the armature A and field winding F to a point intermediate the armature windings M and G; and a suitable switching device S for varying the active amount of the resistor R in circuit, in any well-known manner.

The armature winding M of the dynamotor is thus connected, through the resistor R, across the main motor armature A, while the generator-armature winding G is connected in circuit with the resistor R in parallel relation to the main field winding F.

Inasmuch as the particular system of control for starting and initially accelerating the main motor is not essential to our present invention, we have not deemed it necessary to illustrate our invention in any greater detail. Assuming that the main motor is running at a speed suitable for regenerative

operation and that the connections shown in Fig. 1 have been effected to permit of the regeneration of energy to the supply circuit, the operation of the system may be set forth as follows: As indicated by the arrow heads, the main regenerative circuit is established from the conductor Ground, through conductors 1 and 2, the generator-armature winding G, a predetermined portion of the resistor R, the armature A of the main dynamo-electric machine, and thence to the supply-circuit conductor Trolley. The field circuit for the main machine includes the generator armature G, the above-mentioned predetermined portion of the resistor R, through which the field current flows in the same direction as the regenerated current, the field winding F and conductors 3 and 2 to the generator armature G. The excitation of the field winding F is thus produced by the difference in voltage between the electro-motive force generated in the armature G and the combined ohmic drops in the resistor R that are produced by the regenerated and the field-winding currents. Consequently, if the regenerated current tends to increase by reason of fluctuations in the supply-circuit voltage, or for any other reason, the ohmic drop of the resistor R is correspondingly increased, thus inherently, relatively rapidly and without the use of any auxiliary apparatus, such as relays, reducing the excitation of the main field winding F to the same degree and, thus, in turn, decreasing the regenerated voltage that is produced by the main motor armature A. In case the regenerated current tends to decrease, the reverse action takes place and the regenerated voltage of the armature A is relatively quickly brought up to a predetermined value. In this way, undesirable surges of the regenerated current are obviated and the system, as a whole, inherently tends to regenerate a substantially constant current. As the speed of the regenerating machine decreases during the braking period, the resistor R may be gradually and correspondingly short-circuited by the switching device S, in accordance with any suitable and familiar practice.

In the system shown in Fig. 2, substantially the same apparatus is employed as is described in connection with Fig. 1, but the connections of the main field winding F are modified. The main field-winding circuit, as indicated by the arrow-heads, comprises the generator armature G, the field winding F, conductors 4 and 5, and the resistor R which is connected to the generator G at a junction-point 5^a. The main regenerative circuit is established from the conductor Ground, through conductors 6 and 5, the resistor R, through which the combined field and regenerative currents flow in the same direction, the junction-point 5^a, conductor 7,

the armature A and thence to the supply-circuit conductor Trolley.

The dynamotor is here shown as provided with only a series-connected field-magnet winding E1. It will be understood that either the shunt-excited or the series-excited dynamotors already mentioned, or the compound-excited type of dynamotor that is shown in Fig. 4, may be employed, as desired. However, the series-excited dynamotor of Fig. 2 has an important advantage in that the speed and the voltage output of the exciting armature follow the variations of supply-circuit voltage, as reflected in the changes of current in the common series field winding for both armature windings of the dynamotor. Thus, at all times, the generator voltage bears a substantially constant ratio to the voltage of the supply circuit.

Whereas, in the system illustrated in Fig. 1, it will be observed that the generator armature winding G carries both the regenerative and the field-winding currents and, consequently, must be of relatively large capacity, in the system shown in Fig. 2, the generator G is connected in circuit to carry only the exciting current of the field winding F and, consequently, may be of relatively small capacity, cost, etc.

The operation of the system shown in Fig. 2 is similar to that shown in Fig. 1, since, for example, if the regenerated current increases, the increased ohmic drop in the resistor R will inherently effect a corresponding decrease in the excitation of the field winding F, thereby maintaining a suitable voltage at the terminals of the main armature A.

In Fig. 3, a suitable battery B is substituted for the dynamotor or motor-generator of the system shown in Fig. 2, the corresponding circuit connections being otherwise the same. The battery B is thus adapted to excite the field winding F and to send current through the resistor R in the same manner as the generator G, while the regenerated current again traverses the resistor R, the conductor 7 and the main armature A. It is believed that no further description of the operation is required.

Whereas the systems described are particularly adapted for regenerative operation, they may readily be employed to advantage also during the accelerating period of the motor. For example, consider the system of Fig. 1 when the main motor is accelerating or is running at its balancing speed, the direction of currents in the various circuits being indicated by dotted arrows. It will be observed that the field winding current flows in the same direction as during regeneration, and this current is shown as coming partially from the "Trolley" through the armature A in the reverse direction and partially from the generator armature G.

through the resistor R in the same direction as during the regenerating period. However, it will be understood that, at certain periods, the armature current may be sufficiently heavy to supply the field current through the generator G. The inherent regulating action of the resistor R, which is hereinafter more fully set forth, obtains irrespective of the direction of current there- 16 through.

Consequently, the dynamo-electric machine may change from an electrically-driven motor to a momentum-driven generator by predetermined control manipulation by an operator or by reason of fluctuations in supply-circuit voltage, inherently, smooth and without requiring either automatic or manual operation of relays or other such control devices and without necessitating the relative reversal of armature and field winding which has been essential in prior systems.

Moreover, whenever the armature current increases during acceleration, the main field current is also increased, not only in accordance with the armature current but also from the generator armature G, as more fully explained in connection with Fig. 4. It is believed that no further exposition of the accelerating operation of the systems shown in Fig. 2 and in Fig. 3 is required, because of their similarity to the operations just recited.

Another feature of importance is that our system is inherently and immediately responsive to variations in armature current or fluctuations in supply-circuit voltage during either acceleration or regeneration, inasmuch as it is not necessary to manipulate, either automatically or otherwise, any control devices having an inherent time element, for the variations in ohmic drop in the resistor R immediately effect the desired change in field excitation of the machine. Neither is it necessary to have a time element in regulation by reason of depending upon magnetic changes in exciting machines, as employed in some prior systems.

In other words, our system provides a resistor comprising a means independent of the auxiliary source of energy for the field winding for varying the field-winding voltage while maintaining the field-circuit impedance conditions unchanged, to inherently compensate for relatively small or temporary variations between supply circuit and armature voltage during either acceleration or regeneration, and means, in the form of any suitable switching device, for varying the field-circuit impedance conditions to compensate for relatively large or continued variations, for example, as the machine speed continually decreases during regenerative operation.

In Fig. 4, a modified accelerating system is illustrated, comprising the main armature

A, the field winding F, a dynamotor having the armatures M and G, and the exciting field windings E and E1, and a plurality of translating devices, such as resistors R1 and R2, that are respectively provided with suitable gradual-short-circuiting switching devices S1 and S2. 70

The resistor R1 and the motor-armature winding M of the dynamotor are connected in parallel relation to the main armature A, 75 while the generator armature G is adapted to energize the main field winding F through the resistor R2.

Assuming that the main field winding F normally receives a portion of its current 80 from the supply-circuit conductor Trolley through the armature A and an additional portion from the generator armature G, and that the system has been started into operation in any suitable manner so that the resistor R1 is short-circuited, while the resistor R2 is included in circuit, the operation of the system, in so far as our invention is concerned, may be described as follows: If the motor current traversing the armature A is 85 suddenly increased, for any reason, the immediate effect is to increase the voltage across the terminals of the field winding F and, consequently, reduce the current traversing the resistor R2 from the generator-armature 90 winding G. However, this action results in a decreased ohmic drop in the resistor R2, and the final effect is such as to increase the portion of the voltage of the generator G that is impressed upon the terminals of the 100 field winding F, thereby strengthening the main-motor excitation and preventing an undesirable surge of current. In this way, an increase of the main current traversing the armature A, in turn, indirectly produces 105 an increased excitation of the field winding F from the generator winding G, thus giving the accelerating motor a compound operating characteristic.

The same result may be obtained if the 110 resistor R2 is short-circuited while the resistor R1 is actively connected in circuit. Provided the motor current increases under such conditions, the instantaneous value of current traversing the generator-armature 115 winding G will be correspondingly decreased for the reasons recited above, with the immediate result that the current in the motor-armature winding M of the dynamotor will be correspondingly reduced, accompanied by 120 a corresponding decrease of the ohmic drop in voltage across the resistor R1. However, the final result of such changes is to increase the voltage impressed upon the motor-armature winding M from the main supply circuit by reason of the reduced ohmic drop across the resistor R1, which action, in turn, 125 will increase the speed of the dynamotor and the voltage delivered by the generator armature winding G thereof, to finally effect 130

a predetermined increase of the excitation of the main motor field winding F.

We do not wish to be restricted to the specific circuit connections or arrangement 5 of parts herein set forth, as various modifications thereof may be made within the spirit and scope of our invention. We desire, therefore, that only such limitations shall be imposed as are indicated in the ap- 10 pended claims.

We claim as our invention:

1. A system of control comprising a main 15 dynamo-electric machine having an armature and a field-magnet winding, auxiliary dynamo-electric means connected to excite the main field winding and provided with a plurality of armature windings and a field winding excited by the current of one of the auxiliary armature windings, and a resistor, the circuit connections being such that the main armature current and the auxiliary exciting current traverse said resistor in the same direction.

2. A system of control comprising a main 25 dynamo-electric machine having an armature and a field-magnet winding, auxiliary dynamo-electric means connected to excite the main field winding and provided with a series field winding, and a resistor, the circuit connections being such that the main armature current and the auxiliary exciting current traverse said resistor in the same direction.

3. In a system of control, the combination 35 with a supply circuit, and a main dynamo-electric machine having an armature and a field-magnet winding, of means including an auxiliary exciting armature winding associated therewith for inherently imparting to the main machine a negative compound characteristic during regeneration, and a series-excited driving armature winding for said exciting armature winding.

4. In a system of control, the combination 45 with a supply circuit, and a main dynamo-electric machine having an armature and a field-magnet winding, of a translating device connected in series relation with the main armature across the supply circuit, an auxil-

iary exciting armature winding connected 50 through said field winding across said translating device, and a driving armature winding for said exciting armature winding energized from the supply circuit and provided with a series-related exciting wind- 55 ing.

5. In a system of control, the combination with a supply circuit, and a main dynamo-electric machine having an armature and a field winding, of means including an auxiliary exciting armature winding connected to 60 the machine to impart thereto a negative compound characteristic during regeneration, a driving armature winding for said exciting armature winding, and means for 65 exciting both auxiliary armature windings in accordance with the load upon said driving armature.

6. In a system of control, the combination with a supply circuit, and a main dynamo- 70 electric machine having an armature and a field-magnet winding, of means including an auxiliary exciting armature winding associated therewith for inherently imparting to the main machine a negative compound charac- 75 teristic during regeneration, and means co-operating with said exciting armature winding to insure a constant ratio of the voltage thereof to the supply-circuit voltage.

7. In a system of control, the combination 80 with a supply circuit, and a main dynamo-electric machine having an armature and a field-magnet winding, of a resistor, a dynamotor driven from said supply circuit and having its generating armature winding connected to the machine through said resistor to impart a negative compound characteristic thereto during regeneration, the excitation of the dynamotor being of such character as to insure a constant ratio of the generated voltage thereof to the supply-circuit 90 voltage.

In testimony whereof, we have hereunto subscribed our names this 29th day of April, 1915.

RUDOLF E. HELLMUND.
RALPH E. FERRIS.
